(57) **CLAIM**

The ornamental design for a mounting device for a video camera, as shown and described.

DESCRIPTION

FIG. 1 is a perspective view of a mounting device for a video camera showing our new design coupled to a video camera accessory;

FIG. 2 is a second perspective view of thereof;

FIG. 3 is a third perspective view thereof presented in an exploded view with a claimed mounting plate portion decoupled from a claimed base portion;

FIG. 4 is a fourth perspective view thereof presented in an exploded view with the claimed mounting plate portion decoupled from the claimed base portion;

FIG. 5 is a front elevation view thereof;

FIG. 6 is a rear elevation view thereof;

FIG. 7 is a top plan view thereof;

FIG. 8 is a bottom plan view thereof;

FIG. 9 is a left side elevation view thereof; and

FIG. 10 is a right side elevation view thereof.

FIG. 11 is a front elevation view of the mounting device for a video camera showing our new design separated from the video camera accessory with the claimed mounting plate removed to show the underlying base portion;

FIG. 12 is a rear elevation view thereof;

FIG. 13 is a top plan view thereof;

FIG. 14 is a bottom plan view thereof;

FIG. 15 is a left side elevation view thereof; and,

FIG. 16 is a right side elevation view thereof.

Broken lines in the drawings depict environmental subject matter and form no part of the claimed design.
